UNITED STATES PATENT OFFICE

173,193

DOUBLE LENS CAP

Arthur H. Crapsey, Jr., Rochester, N. Y., assignor
to Eastman Kodak Company, Rochester, N. Y.,
a corporation of New Jersey

Application February 3, 1954, Serial No. 28,819

Term of patent 14 years

(Cl. D61—1)

To all whom it may concern:

Be it known that I, Arthur H. Crapsey, Jr., a citizen of the United States, residing at Rochester, in the county of Monroe and State of New York, have invented a new, original, and ornamental Design for Double Lens Cap, of which the following is a specification, reference being had to the drawings, forming a part thereof, in which:

Fig. 1 is a top plan view of a double lens cap, illustrating my new design;

Fig. 2 is a side elevation thereof; and

Fig. 3 is a bottom plan view of the same.

I claim:

The ornamental design for a double lens cap, as shown.
